UNITED STATES PATENT OFFICE.

FRANK C. WHITE, OF MERIDEN, CONNECTICUT, ASSIGNOR TO THE WILCOX & WHITE COMPANY, OF MERIDEN, CONNECTICUT, A CORPORATION OF CONNECTICUT.

AUTOPNEUMATIC MUSIC-PLAYING PIANO.

No. 886,908.

Specification of Letters Patent.

Patented May 5, 1908.

Application filed December 14, 1907. Serial No. 406,538.

To all whom it may concern:

Be it known that I, FRANK C. WHITE, a citizen of the United States, residing at Meriden, county of New Haven, State of Connecticut, have invented certain new and useful Improvements in Autopneumatic Music-Playing Pianos, of which the following is a full, clear, and exact description.

My invention relates to auto-pneumatic music playing pianos, and has for its object a superior construction and arrangement of parts whereby great compactness is afforded and the various parts are rendered accessible.

Heretofore it has been practically impossible to replace strings or adjust the auto-pneumatic mechanism without first removing much of the mechanism or many of the parts. By my construction, this is avoided and all the parts are rendered accessible by simply removing the lower panel.

In the drawings, Figure 1 is a front view of the lower part of a piano, the lower panel and the strings of the harp being removed; Fig. 2 is a sectional view on the plane of the line 25 *x*—*x*, looking in the direction of the arrow; Fig. 3 is a front view of the lower part of the harp; Fig. 4 is a side view of the crank shaft mechanism employed between the pedals and the feeder or exhaust bellows; Fig. 5 is a 30 plan view of the mechanism shown in Fig. 4.

1 represents a part of a piano case, which may be of any suitable construction.

2 is the removable lower or front panel which hides from view the auto-pneumatic mechanism and the harp 3. The harp 3 is provided with strings 4—4 which are secured at their lower ends to the pins 5—5, (Fig. 3).

Since the action and the different valves and levers form no part of my invention and 40 interfere in no way with the open space making the different parts accessible, the same have not been shown. Placed at or near each end are the exhaust or feeder bellows 6—6, which are suitably connected to the 45 pedals 7—7 by means of laterally suspended crank shafts 8—8, or any other suitable operative means. The feeder bellows 6—6 are placed far enough forward of the harp 3 to 50 allow a tuner or repairer to place his hand or arm between the same for the replacing of strings, or doing any other work that may become necessary. The bellows 6—6 are

connected by a trunk 9, which is divided into suitable passages and has its central portion narrowed so as to take up little space.

55

At or near one end of the trunk 9 is an equalizing bellows 10, which is in communication with the action (not shown) through the wind-ways 11—11. 12 is the motor, also at one side. On the trunk 9 and near the 60 motor 12 is a motor regulator 13, of any suitable construction.

The particular method of mounting the 65 pedals 7—7 and connecting them to the bellows 6—6 is immaterial, but the preferable form is to pivotally mount the yoke 14 to the frame. Yoke 14 has a lever 15 attached to its lower side. One end of said lever is provided with a roller upon which the pedal 7 rests. A link 16 connects the yoke 14, and 70 the crank shaft 8 is also connected to the back of the bellows 6 by means of a link 17. It will be readily seen by reference to Figs. 4 and 5, that when the pedal 7 is pressed down, the yoke 14 is caused to rock. This in turn 75 rocks the crank shaft 8 by means of the link 16. When the crank shaft 8 is rocked, the bellows 6 is caused to expand through the medium of the link 17.

In the various forms of construction, all of 80 the parts of the auto-pneumatic mechanism are spaced far enough from the harp to allow a hand or arm to be inserted for the replacement of strings, or for any other purpose desired, ample space being provided around 85 and back of the trunk 9 to permit of this work.

What I claim is:

1. In an auto-pneumatic music playing instrument, a harp, strings carried thereby, a 90 case inclosing said harp, pneumatic playing device including feeder and equalizer bellows, a motor and regulator, said parts being arranged at or near each edge of the harp, and a trunk connection between the lower ends of 95 said parts, all of said parts being spaced away from said harp and affording an intermediate clearance opening above the said trunk to give access thereto.

2. In an auto-pneumatic music playing instrument, a harp, strings carried thereby, a 100 case, a feeder bellows at or near one edge of said harp and within said case, a wind trunk extending across the space in front of said

harp and leaving a space above and to the rear of said trunk to afford access to said harp.

3. In an auto-pneumatic music playing instrument, a harp, strings carried thereby, a case, exhaust bellows, a motor and regulating mechanism, said parts being arranged at the ends of said case, said harp being accessible between said parts, and a trunk connection

partially occupying the space between the lower ends of said parts, the space above said trunk being open, substantially as and for the purpose described.

FRANK C. WHITE.
